(57) **CLAIM**

The ornamental design for a platen press, as shown and described.

DESCRIPTION

FIG. 1 is a perspective view of a platen press showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines in the drawings illustrate environmental material that forms no part of the claimed design.

The bottom is not shown, as it is devoid of surface ornamentation.
